[57] CLAIM

The ornamental design for a reflective pet vest, as shown and described.

DESCRIPTION

FIG. 1 is a top plan view of a reflective pet vest showing my new design;

FIG. 2 is a bottom plan view thereof; and,

FIG. 3 is a side perspective view thereof, the broken lines are for illustrative purposes only and form no part of the claimed design.

1 Claim, 2 Drawing Sheets

FIG. 1

FIG. 3
